CLAIM

The ornamental design for a changeable character stamp, as shown and described.

DESCRIPTION

FIG. 1 is a right front perspective view of a changeable character stamp taken from above;

FIG. 2 is a right front perspective view of the changeable character stamp taken from under;

FIG. 3 is a front view of the changeable character stamp;

FIG. 4 is a rear view of the changeable character stamp;

FIG. 5 is a left side view of the changeable character stamp;

FIG. 6 is a right side view of the changeable character stamp;

FIG. 7 is a top plan view of the changeable character stamp;

FIG. 8 is a bottom view of the changeable character stamp;

FIG. 9 is a front view of the changeable character stamp in which a cover cylinder is raised so as to be able to change stamping characters, the rear view being a mirror image thereof; and,

FIG. 10 is a right side view of the changeable character stamp in which a cover cylinder is raised so as to be able to change stamping characters therein, the left side view being a mirror image thereof.
